UNITED STATES PATENT OFFICE.

HENRY BERGER, OF NEW YORK, N. Y.

DESIGN FOR CENTER-PIECE.

Specification forming part of Design No. 7,352, dated April 7, 1874; application filed March 27, 1874.
 [Term of Patent 14 years.]

C.

To all whom it may concern:

Be it known that I, HENRY BERGER, of the city, county, and State of New York, have invented a new and original Design for Center-Piece; and I do hereby declare the following to be a full, clear, and exact description thereof, which will enable those skilled in the art to carry out the same, reference being had to the accompanying drawing forming a part of this specification, which drawing shows a face view of my design.

This invention consists in the design of a central button encircled by a series of radiating segmental panels, outside of which are alternate rosettes and escutcheons, inclosed and supported by ornamental shields.

In the drawing, the letter A designates the central button of my design, which is of a round or circular shape, and is ornamented with scalloped edges *a*. Encircling this button are segmental panels B, which are ornamented as shown, being divided by radiating spaces *b*. These panels are surrounded by a

series of circular rosettes, C, and ram's-horn escutcheons D, which alternate with each other, and are interspersed with ornamental tracery or scroll-work. Said rosettes and escutcheons rest upon the face of shields E, which are arranged in a circle, and have stepped or double edges, as shown.

What I claim as new, and desire to secure by Letters Patent, is—

1. The combination of the radiating segmental panels B with the central button A, as shown and described.

2. The rosettes C and escutcheons D, alternating with each other, and supported on shields E, in combination with the radiating segmental panels B and central button A, as shown and specified.

This specification signed by me this 28th day of February, 1874.

HENRY BERGER.
